UNITED STATES PATENT OFFICE.

BYRON W. PIERCE, OF APPLETON, WISCONSIN.

ROTARY IGNITER.

1,130,628.

Specification of Letters Patent.

Patented Mar. 2, 1915.

Application filed February 18, 1913, Serial No. 749,271. Renewed December 10, 1914. Serial No. 876,537.

To all whom it may concern:

Be it known that I, BYRON W. PIERCE, a citizen of the United States, residing at Appleton, in the county of Outagamie and 5 State of Wisconsin, have invented certain new and useful Improvements in Rotary Igniters, of which the following is a specification, reference being had therein to the accompanying drawing.

10 This invention relates to rotary igniters, and the principal object of the same is to provide a device which will do away with the necessity for the use of spark coils and commutator or timer now used with other 15 types of igniters, and securing the advance and retard of the spark through gear mesh and securing more perfect combustion and greater efficiency in the motor power and automatic cleaning of points of contact.

20 Another object of the invention is to provide an igniter which will have a comparatively small number of parts and which will be caused to operate very efficiently.

Another object of the invention is to provide 25 an igniter having an improved type of contact members which make the spark explode the gas in the cylinder more perfectly.

Another object of the invention is to provide 30 an igniter which may be easily taken apart to permit the same to be repaired.

With these and other objects in view this 35 invention consists of certain novel combinations, constructions, and arrangements of parts as will be hereinafter fully described and claimed.

In the accompanying drawing:—Figure 1 is a view showing the casing in section and the remaining portions of the igniter in elevation. Fig. 2 is a vertical sectional view along the line 2—2, in Fig. 1. Fig. 3 is a transverse sectional view along the line 3—3, in Fig. 1. Fig. 4 is a transverse sectional view along the line 4—4, in Fig. 1. Fig. 5 is a fragmentary view of the upper portion of the center pin.

This invention comprises a housing 10 provided with a screw cap 11 and having oppositely disposed bearings 12 through 50 which the shaft 13 passes and which are provided with bushings 14 forming supports for the shaft 13. This cover is connected with the body portion by means of the threads shown at 15 and it will, therefore, 55 be seen that when it is desired to obtain ac-

cess to the interior of the housing that it is simply necessary to unscrew the cover.

A hollow casing 16 is positioned beneath the housing 10 and is provided with a cup 17 having a threaded upper end portion 18 which is screwed into an internally threaded neck 19 extending from the housing 10. This cup 17 is provided with flattened faces so that the cup may be engaged by a suitable wrench, and thus firmly connected with the housing and also so that the casing 16 may have its threaded portion 20 screwed into the engine cylinder.

A hollow lining 21 which is preferably formed of porcelain or some other similar substance extends through the lower portion of the casing 16 and is provided with an enlarged head 22 which is positioned in the lower portion of the cup 17. A protecting washer 23 preferably formed of asbestos is placed beneath the head 22, thus preventing it from being broken when the adjusting nut is tightened. Above this head 22 there is placed a collar 24 which has its inner end portion 25 enlarged as clearly 80 shown in Fig. 2, and which is held in spaced relation to the head 22 by a packing 26 of asbestos or any other suitable substance. A metallic lining 27 extends through the collar 24 and protects the collar, thus preventing it from being broken. If desired a similar lining may be placed within the member 21. A gland nut 28 is screwed into the cup 17 and engages the enlarged inner end portion 25 of the collar 24, thus forcing the 90 same inwardly and holding the various elements in the cup in their desired position.

A stem 29 extends through the casing and is provided with an enlarged head 30 which fits into a pocket 31 formed in a beveled gear wheel 32. This gear wheel 32 meshes with a gear wheel 33 mounted upon the shaft 13 and it will, therefore, be seen that when the shaft 13 turns the igniter will be secured to operate. A pin 32 extends partially 100 through the gear wheel 32 and has its inner end embedded in a slot 35, thus permitting the stem 29 to slide longitudinally, but preventing independent rotary motion by the stem and gear wheel 32. A spring 36 is 105 coiled about the upper portion of the stem beneath the head 30 and normally holds the stem in the position shown in Fig. 2. The lower end of this stem is threaded and carries a spacing ring 37 which ring holds the 110

disk 38 in spaced relation to the plate 39. This plate 39 is held in place by the rivets 40 and carries the platinum points 41 which are engaged by the point on the arm 42 as the stem rotates. It should be noted that the spring yieldably holds the stem in the position shown in Fig. 2, thus permitting it to be brought into contact with the points 41, but at the same time permitting the point on the arm 42 to ride over the points 41, and thus preventing the igniter from being prevented from rotating. The disk is held in place by a securing nut 43 which is locked upon the stem by the locking washer 44.

When using this device the threaded portion 20 of the casing is screwed into the cylinder of the engine with its inner end extending into the explosive chamber. When 20 the shaft 13 is rotated it causes the stem to rotate, and thus the point on the arm 42 will be brought successively into engagement with the points 41 and cause a spark every half revolution. If it is desired to repair the igniter it can be easily removed and the several parts disassembled. The worn out portions can then be replaced by new ones and the igniter be assembled and put back in place.

Having thus described the invention what is claimed as new, is:—

1. An igniter comprising a housing, a casing carried by said housing, said casing being provided with an enlarged upper end portion forming a cup, a lining of insulating material extending through said casing and provided with an enlarged upper end portion positioned in the lower end portion of said cup, a protecting washer between the enlarged upper end portion of said lining and the bottom of said cup, a collar positioned in the upper portion of said cup, a protecting washer between said collar and the inner end portion of said lining, a gland screwed into said cup for holding said collar in place, a stem passing through said casing, a contact arm carried by said

stem, a plate carrying contact points carried by said casing and adapted to be engaged by said contact arm when said stem is rotated, and means for rotating said stem. 50

2. A device of the character described comprising a housing, a casing carried by said housing and provided with cup shape upper end portion, a stem extending 55 through said casing, a lining of insulating material positioned in said casing and surrounding said stem and having its inner end portion formed into an enlarged head positioned in said cup, a collar in said cup surrounding said stem, a protecting washer between said collar and the inner end of said lining, means for holding said collar in place, a plate carried by said casing, contact points formed upon said plate, a contact arm carried by said stem and engaging said contact points when said stem is rotated, and means for rotating said stem. 60

3. A device of the character described comprising a casing, a stem passing through 70 said casing and insulated therefrom, a plate carried by said casing, contact points carried by said plate, a contact arm carried by said stem, an enlarged head at the upper end of said stem, said stem being provided adjacent 75 its upper end with a longitudinally extending slot, a gear mounted upon the upper end portion of said stem and provided with a pocket in which the enlarged head fits, a pin extending through said gear having its 80 inner end extending into said slot for slidably connecting said stem with said gear, and a spring surrounding said stem between the enlarged head of said stem and the bottom of the pocket formed in said gear 85 whereby said contact arm will be normally held in a position to engage said contact points and permitted to ride over the same.

In testimony whereof I hereunto affix my signature in presence of two witnesses.

BYRON W. PIERCE.
